CLAIM

The ornamental design for a shoe sole, as shown and described.

DESCRIPTION

FIG. 1 is a bottom plan view of a shoe sole showing an alternate embodiment of my new design;
 FIG. 2 is a left side elevational view thereof;
 FIG. 3 is a right side elevational view thereof;
 FIG. 4 is a front elevational view thereof;
 FIG. 5 is a rear elevational view thereof;
 FIG. 6 is a right side perspective view thereof; and,
 FIG. 7 is a left side perspective view thereof.

The broken line showing of a shoe midsole in the figures is environmental only and forms no part of the claimed design.
